UNITED STATES PATENT OFFICE.

REUBEN MILLER, OF PITTSBURG, PENNSYLVANIA, ASSIGNOR TO HIMSELF,
WILLIAM METCALF, AND CHARLES PARKIN, OF SAME PLACE.

DESIGN FOR A BANK-CHECK.

SPECIFICATION forming part of Design No. 12,076, dated December 21, 1880.

Application filed September 24, 1880. Term of patent 14 years.

To all whom it may concern:

Be it known that I, REUBEN MILLER, of Pittsburgh, county of Allegheny, State of Pennsylvania, have invented or produced a new and original Design for Bank-Checks; and I do hereby declare the following to be a full, clear, concise, and exact description thereof, reference being had to the accompanying drawing, making a part of this specification, which illustrates my improved design for bank-checks.

The leading features of this design consist, first, in the arrangement of the name of the bank on which the check is drawn with relation to the blanks for name of payee and the amount to be paid; and, second, in the manner of printing at the upper left-hand corner of the check the name or other proprietary mark of the maker of the check.

The face of the check, as represented in the drawing, is ruled or spaced in four horizontal lines of blanks, the upper blanks, a a', being for number and date respectively, the next lower, b, being for the name of the payee, the third line, c, being for the amount to be paid, and the fourth (divided) line, d d', being for the amount of the check in numerals and for the signature of the maker of the check. The arrangement thus far specified is that which is in ordinary use on bank-checks, except that no space or line is especially set apart for the name of the bank on which the check is drawn.

To illustrate this part of the design I have assumed the check to be drawn on "The Bank of Pittsburg," and the letters composing such name are arranged in a reflex or double-curve line, beginning at or near the left hand of blank c (the blank for the amount of the check) and extending in curved line, as stated, upward across and more or less along and over the blank b, (the blank for the name of the payee.) These letters are, by preference, of comparatively large size, or capitals, and printed or tinted with ink of light color, so that words 45 or symbols written over them in ordinary writing-ink may be legible. This arrangement of the name of the bank gives to the check a distinctive and neat appearance, which is its main purpose.

At the upper left-hand corner I arrange another distinguishing feature of this check, consisting in its main features of a dark shaded or clouded ground, e, representing a radiation of light, and across the face of such ground is 55 printed on a scroll, e', in white letters or in intaglio, the name of the maker or drawer of the check, which in this case I have assumed to be the firm of "Miller, Metcalf & Parkin," and also such other words of place or direction, or symbols i and monograms i', as may serve to indicate to the eye the source of the check or the person or firm by whom it is made, and at the same time be a distinguishing mark or feature by which this particular design of 65 check may be readily recognized.

I claim as my invention—

The design for bank-check herein shown and described, the same consisting of the arrangement of the name of the bank on which the 70 check is drawn in a reflex or double curve line crossing and partially covering the blanks designed for the name of the payee and the amount to be paid, the letters composing the name of such bank being of large size and 75 printed or shaded with light-colored ink, in combination or connection with a shaded or clouded ground at the upper left-hand corner of the check, across which is printed in white the name or other proprietary mark, or both, 80 of the maker of the check, as shown and described.

In testimony whereof I have hereunto set my hand.

REUBEN MILLER.
